Primary Examiner — Stacia Cadmus(74) *Attorney, Agent, or Firm* — J. A. Thurnau, Esq.; T. A. Dougherty, Esq.; P. N. Dunlap, Esq.(57) **CLAIM**

The ornamental design for a valve cap, as shown and described.

DESCRIPTION

FIG. 1 is a side elevation view.

FIG. 2 is a top plan view.

FIG. 3 is a bottom plan view.

FIG. 4 is a cross-section view taken along line 4—4 in FIG. 2; and,

FIG. 5 is a perspective view.

The broken line showing of the valve cap is for the purpose of illustrating gripping ridges and forms no part of the claimed design.
